UNITED STATES PATENT OFFICE

143,629

DESIGN FOR A CABINET FOR HIGH-FREQUENCY ELECTRICAL HEATING APPARATUS

Vernon W. Sherman, Summit, and Louis Kniep, East Orange, N. J., and Walter H. Rothaug, New York, N. Y., assignors to Federal Telephone & Radio Corporation, New York, N. Y., a corporation of Delaware

Application March 22, 1945, Serial No. 118,630

Term of patent 14 years

(CL D28—5)

To all whom it may concern:

Be it known that we, Vernon W. Sherman, Louis Kniep and Walter H. Rothaug, citizens of the United States, residing at Summit, East Orange and New York city, in the counties of Essex and New York and the States of New Jersey and New York, have invented a new, original, and ornamental Design for a Cabinet for High-Frequency Electrical Heating Apparatus, of which the following is a specification, reference being had to the accompanying drawing, forming part thereof in which the single figure in the drawing

is a front perspective view of a cabinet for high frequency electrical heating apparatus showing my new design.

Both sides of the cabinet are similar and the rear portion is a plain flat surface.

We claim:

The ornamental design for a cabinet for high-frequency electrical heating apparatus, as shown and described.

VERNON W. SHERMAN.
LOUIS KNIEP.
WALTER H. ROTHAUG.
